U.S. Cl. D71—1 V

FIG. 1 is a perspective view of a convertible houseboat-camping trailer embodying my new design;

FIG. 2 is an end elevational view thereof as seen from the left side of FIG. 1;

FIG. 3 is a further perspective view thereof as seen from the background of FIG. 1; and

FIG. 4 is a perspective view thereof similar to FIG. 3, but with the upwardly swingable bow and stern end portions swung upwardly to their folded positions in order to adapt the convertible houseboat-camping trailer to be more readily trailed behind a towing vehicle.

The broken line showing of the wheel running gear, outboard motor, and towing tongue shown in FIGS. 1, 2, 3 and 4 is for illustrative purposes only.

I claim:
